CHILD'S HANDBAG

Sidney Hyman, New York, N. Y.

Application December 22, 1955, Serial No. 39,440

Term of patent 3½ years

(Cl. D87—3)

Fig. 1 is a front perspective view of a child's handbag, showing my new design;

Fig. 2 is a view similar to Fig. 1, with the cover opened; and

Fig. 3 is a rear elevational view of Fig. 1.

I claim:

The ornamental design for a child's handbag, as shown.
